BOTTOM TAP LADLE MECHANISM

Edwin William Carter, San Leandro, Calif.

Application November 23, 1949, Serial No. 129,077

4 Claims. (Cl. 22—85)

1

My invention relates to ladles for handling molten metal and the like of the type having a bottom opening for the discharge of the ladle contents, and is more particularly directed to the provision of an improved mechanism for supporting the plug employed for sealing the bottom opening.

Bottom tap ladles, as they are termed by the foundry industry, are considered highly desirable, particularly by steel foundries, for several reasons, such as the virtual exclusion of slag from the molten metal discharged through the bottom pouring opening. These ladles usually employ a long refractory plug extending upwardly from the pouring hole in the bottom of the ladle through the ladle to a gooseneck, which is secured to the plug above the ladle lip and is supported by a reciprocating mechanism mounted on the outside of the ladle. By actuating the reciprocating mechanism, the operator may raise and lower the plug, thus opening and closing the bottom pouring opening.

The vertical leg of the gooseneck is usually carefully machined to form a long taper having an angle of five degrees or less with respect to the axis of the leg and is received by a correspondingly machined opening in a bracket mounted on the reciprocating mechanism. The tapered surface is usually quite long, since the parts are heavy and must be accurately held in position. This type of connection has proven troublesome in practice because of its tendency to freeze, as for example by rusting of the surfaces or the inclusion of foreign material. Violent hammering, as well as the expenditure of considerable time and effort, is frequently necessary to remove the gooseneck from the reciprocating mechanism, as for example when a new lining for the ladle is to be dried. In addition the long tapered surfaces are both difficult and expensive to machine and maintain.

The primary object of my invention is to provide a bottom tap foundry ladle having improved connecting means for removably supporting the gooseneck on the reciprocating mechanism, which will accurately hold the gooseneck in position, but which permits removal of the gooseneck at all times without difficulty and which requires a minimum of precision machining.

Other objects of my invention include the provision of various novel components and assemblies, and will be fully disclosed in the course of the following detailed description and in the appended drawings, in which:

Fig. 1 is a partially sectioned elevation of a

bottom tap foundry ladle incorporating my invention;

Fig. 2 is a partially sectioned elevation of the plug operating mechanism illustrated in Fig. 1;

Fig. 3 is a partially sectioned elevation of the connection between the gooseneck and the reciprocating mechanism;

Fig. 4 is a partial cross section illustrating a modification of a portion of the gooseneck-supporting means; and

Fig. 5 is a partial cross section through a modified form of connection between the gooseneck and the reciprocating mechanism.

In brief, the objects of my invention are accomplished by forming on the upright leg of the gooseneck a cylindrical section immediately below a frusto-conical section, the face of which forms an angle of not less than 10 degrees nor more than 80 degrees with the axis of the leg and is preferably on the order of 45 degrees. A pin is formed on the lower end of the leg and engages an opening in a pilot lug fixed to the reciprocating mechanism. Above the pilot lug or bracket is a large lateral bracket having a cylindrical bore to receive the cylindrical portion of the leg, and which is provided with a frusto-conical depression in its upper face immediately surrounding the cylindrical bore in which the frusto-conical section of the vertical leg rests. This connection holds the gooseneck firmly in position and maintains the upright leg continuously in alignment with the reciprocating mechanism. Despite this, however, the gooseneck may be easily removed at any time without effort.

My invention is illustrated in greater detail in the drawings, wherein I have shown a ladle, generally designated 10 having a shell 11, a lining 12, and a bottom 13, in which is formed an opening, indicated at 14. The lining 12 is of conventional refractory material as is an insert 16 placed in the opening 14 and having an axial opening 17 flaring at its upper end to receive the lower end of a plug 18.

The plug 18 includes a refractory cover 19 enveloping a central metal rod 21, which extends upwardly through the ladle 10 to a point above the ladle lip. A gooseneck, generally designated 22, is formed of a laterally extending leg 23 and a vertical leg, generally designated 24. The laterally extending leg 23 is provided with an opening near its end through which the rod 21 extends. Nuts 26 threaded to the rod 21 may be employed to hold the latter firmly in position on the gooseneck.

A frame 27 is pivotally secured to a bracket

28 which is attached as by welding to the ladle shell 11. Reciprocally mounted in the frame 27 is an upright slide 29, the lower end of which is secured to a rack 31. A gear 32 pivoted to the frame 27 engages the rack 31 and is secured to a lever 33 by means of which the gear 32 may be rotated to raise and lower the rack 31 and the slide 29. A threaded eye-bolt 34 extends through the frame 27 and is pivotally secured at its inner end to a bracket 36 welded to the shell 11. A wing nut 38 is threaded to the bolt 34 and engages the frame 27 to tilt the assembly as desired. A threaded lock bolt 39 may also be provided in the frame 27 for engagement with the slide 29 in such manner that rotation of the lock bolt 39 causes the inner end of the bolt to engage the slide 29, thus holding the latter in position.

A lateral bracket 41 is secured to the slide 29 near the upper end of the slide, and is provided with a cylindrical bore, indicated at 42, preferably having an axis parallel to the axis of movement of the slide 29. Immediately below the bracket 41 is a pilot bracket 43 in which I form a relatively small opening in axial alignment with the cylindrical bore 42 in the bracket 41. A frusto-conical depression, indicated at 44, is formed in the upper face of the bracket 41 immediately around the bore 42, the sides or faces of the depression forming an angle of between 10 and 80 degrees and preferably about 45 degrees with respect to the axis of the bore 42.

The vertical leg 24 of the gooseneck 22 includes a cylindrical section 46 machined to fit snugly in the bore 42 and an inverted frusto-conical section 47, which mates with the depression 44. An axial pin 48 is formed on the lower end of the leg 24 and engages the opening in the pilot bracket 48. The parts are dimensioned in such manner that the weight of the gooseneck 22 is carried entirely by the bracket 41 and particularly by the faces of the inverted frusto-conical depression 44. Extending through the leg 24 near the lower face of the bracket 41 is an opening 49 shaped to receive a tapered key (not shown) by means of which the gooseneck 22 may be drawn down into the brackets 41 and 43 and held firmly in position until such time as it is desired to remove the gooseneck. A shield 51 may be secured to the laterally extending leg 23 and projects downwardly between the slide 29 and the shell 11, thus shielding the slide from the destructive influence of excessive radiant heat.

As shown in Fig. 3, I may utilize a pilot bracket 52 having an upwardly extending pin 53 disposed in axial alignment with the cylindrical bore 42 of the bracket 41. In such case, the lower end of the upright leg 24 is bored to receive the pin 53, which thus serves to pilot the leg 24 into position. For most installations I prefer to utilize the form of bracket illustrated in Figs. 1 and 3, wherein the frusto-conical sections of the upright leg and the lateral bracket are in inverted position. In some instances, however, it is preferable to utilize upright frusto-conical sections shown in Fig. 5. When required, therefore, I may substitute for the bracket 41 a bracket 54, having cylindrical bore 56 and an upright conical section 57 formed on the upper of the bracket immediately around the mouth of the bore 56. The vertical leg 24 is provided as before with a cylindrical section 58 and with an upright conical cavity 59 shaped to mate with the conical section 57 in a manner

previously described. It is essential that the face of the conical section form an angle greater than 10 degrees with the axis of the cylindrical bore 56, and will preferably be approximately 45 degrees.

In operation, the gooseneck 22 is lowered into the position indicated in Fig. 1, wherein the frusto-conical sections firmly engage each other and the lower end of the vertical leg 24 is in engagement with the pilot bracket. The plug 18 is secured to the lateral arm 23 and a tapered key is driven into the opening 49. Once the parts are in satisfactory alignment the plug may be locked in position by operation of the lock bolt 39 which engages the slide 29. When it is desired to open the bottom opening, the lock bolt 39 is released and the lever 33 actuated. This raises the slide 29, carrying with it the gooseneck 22 and the plug 18.

To remove the gooseneck 22, the tapered key is removed from the opening 49 and the gooseneck 22 lifted from the brackets 41 and 43. No difficulty will be experienced in performing this operation, since even in the presence of rust and foreign material binding will not occur between the lateral bracket 41 and the vertical leg 24 of the gooseneck. When the gooseneck 22 is again fitted to the slide 29, the vertical leg 24 will assume the same position as previously, since wear is automatically compensated by the frusto-conical sections. Considerable economy will be effected in forming the component parts, since the careful machining necessary to form a long taper is eliminated.

I claim:

1. In a bottom tap ladle for molten metal and the like of the type having an upright plug in the ladle and an upright reciprocating member on the outside of the ladle, the combination therewith of the gooseneck having a laterally extending leg for attachment to the plug and an upright leg having a cylindrical section and a frusto-conical section above the cylindrical section, the face of the frusto-conical section forming an angle with the axis of the upright leg of approximately 45 degrees, a lateral bracket on the reciprocating member having a cylindrical opening for receiving the cylindrical section of the upright leg, and a frusto-conical upper face for engagement with the frusto-conical section of the upright leg, and a pilot bracket on the reciprocating member below the lateral bracket, said pilot bracket including a vertical face disposed for engagement with a mating substantially vertical surface on the lower end of the upright leg for approximately centering the upright leg in the lateral bracket.

2. In a bottom tap ladle for molten metal and the like of the type having an upright plug in the ladle and an upright reciprocating member on the outside of the ladle, the combination therewith of a gooseneck having a lateral leg for attachment to the plug and an integral upright leg, said upright leg defining a frusto-conical bearing surface, concentric with the axes of the upright leg, the face of said conical bearing surface defining an angle of not less than 10° nor more than 80° with said axes and a cylindrical bearing surface also concentric with said axes spaced from the conical bearing surface, the reciprocating member having spaced complementary bearing surfaces formed thereon for engagement with said conical and cylindrical bearing surfaces on the upright leg.

3. In a bottom tap ladle for molten metal and

the like of the type having an upright plug in the ladle and an upright reciprocating member on the outside of the ladle, the combination therewith of a gooseneck having a lateral leg for attachment to the plug and an integral upright leg, said upright leg defining a frusto-conical bearing surface, concentric with the axes of the upright leg, the face of said conical bearing surface defining an angle of not less than 10° nor more than 80° with said axes and a cylindrical bearing surface below the frusto-conical bearing surface, also concentric with said axes spaced from the conical bearing surface, the reciprocating member having spaced complementary bearing surfaces formed thereon for engagement with said conical and cylindrical bearing surfaces on the upright leg.

4. In a bottom tap ladle for molten metal and the like of the type having an upright plug in the ladle and an upright reciprocating member on the outside of the ladle, the combination therewith of the gooseneck having a laterally extending leg for attachment to the plug and an upright leg having a cylindrical section and a frusto-conical section above the cylindrical section, the face of the frusto-conical section form-

ing an angle with the axis of the upright leg of not less than 10° nor more than 80°, a lateral bracket on the reciprocating member having a cylindrical opening for receiving the cylindrical section of the upright leg, and a frusto-conical upper face for engagement with the frusto-conical section of the upright leg, and a pilot bracket on the reciprocating member below the lateral bracket, said pilot bracket including a vertical face disposed for engagement with a mating substantially vertical surface on the lower end of the upright leg for approximately centering the upright leg in the lateral bracket.
